Inventor:
Ralph E. Thompson,
By E. D. Bradenick,
Attorney.

UNITED STATES PATENT OFFICE.

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE.

RAZOR.

Application filed June 4, 1924. Serial No. 717,870.

To all whom it may concern:

Be it known that I, RALPH E. THOMPSON, a citizen of the United States, residing at Brookline, in the county of Norfolk and 5 State of Massachusetts, have invented certain new and useful Improvements in Razors, of which the following is a specification.

The object of my invention is to provide 10 a razor blade having a safety edge, by which I mean an edge which is self-protected in such manner as to prevent it from cutting the skin without materially impairing its effectiveness for shaving. A blade 15 of this character can be employed in or as a part of a razor of the open-blade type, which will then have the protective quality of a safety razor although lacking a guard considered as a part distinct from or sup- 20 plementary to the blade itself, or such a blade can be employed in a razor of any de- sign in which a guard for the cutting edge is provided. In the latter case the razor will have an additional element of safety 25 which is advantageous in the case of safety razors having blades which are adjustable to vary the exposure of the blade edge. My blade also has the advantage, when used in a razor of any of the types having detach- 30 able or interchangeable blades, that it is not liable to cut any one who may handle the detached blade during its period of use or after it has been discarded.

A blade embodying my invention is char- 35 acterized by having its shaving edge provided with a series of alternating sharp and dull portions of limited extent, of which the dull portions are located near enough together to prevent the sharp portions from 40 entering the skin of the user when the blade edge is presented to the skin at any angle at which the skin could be cut, while permitting them to reach the beard in the act of shaving. I have found that in spite of the 45 presence of the dull portions a clean and comfortable shave can be readily obtained by using a blade of this character, it being necessary merely to repeat the strokes of the razor a few times, as is customarily done 50 by most persons in shaving.

One form of my blade is illustrated in

the accompanying drawing, which shows the parts considerably enlarged as compared with their natural size and in which—

Figure 1 is a side elevation of a portion 55 of the blade, and

Figure 2 is a transverse section on the line 2—2 in Figure 1.

In the drawing, 2 indicates a portion of 60 a razor blade of which the shaving edge 65 comprises a series of straight cutting portions 3 alternating with non-cutting portions 4 which are integral with the blade and preferably project slightly beyond the cutting portion 3. This edge formation may 70 be produced by first providing the blade 2 with a thin and smooth but dull edge and then grinding away limited areas at separated points to form the cutting portions 3, leaving the intermediate portions 4 un- 75 sharpened. It is desirable to form the cutting portions 3 by means of two similar bevels, so that their sharp edges will be equidistant from the sides of the portions 4 and will therefore be equally protected there- 80 by on both sides of the blade, and unless the blade itself is very thin it is also de- sirable to bevel the sides of the dull por- 85 tions 4, as shown in Figure 2.

In using the blade above described the 80 spaced arrangement of the dull portions enables the cutting portions to reach the beard when the blade is applied to the skin at a suitable shaving angle, but the skin is protected against being cut either while 85 shaving or during the manipulation of the blade, if detachable, by being held away from the cutting portions by means of the dull portions acting in conjunction with the natural firmness and elasticity of the 90 skin itself and the flesh beneath it. The dull portions also serve to stretch the skin slightly, thereby facilitating the removal of 95 the beard.

The dimensions of the sharp and dull por- 95 tions of a blade edge embodying my inven- tion may be varied within considerable lim- its, according to the factor of safety de- sired. This will depend primarily upon the ratio between the width of the spaces be- 100 tween the dull portions and the distance be- tween the lines in which the sharp portions

and the tops of the dull portions lie, but it will also depend to some extent upon the firmness and elasticity of the skin and flesh of the user. In practise the blade edge should have a factor of safety sufficient to render it usable by persons with thin skins and soft flesh, since in the case of others the cutting portions can be caused to act upon the beard by increasing the pressure of application. The dull portions are preferably made as short in the direction of their length as is practicable, in order to give the blade a maximum amount of cutting edge, and they should of course be made thin enough to enable the sharp portions to reach the skin when the blade is applied at a suitable shaving angle.

I claim:—

1. A razor blade provided at its shaving edges with a series of alternating sharp and dull portions of limited extent, the dull portions being integral with the blade and being so proportioned and spaced as to permit the sharp portions to engage the beard but prevent them from cutting the user. 20

2. A razor blade provided at its shaving edges with a series of integral dull portions having thin rounded edges and separated by sharp portions defined by bevels formed on both sides of the blade between the dull portions. 25

Signed at Boston, Massachusetts, this second day of June, 1924.

RALPH E. THOMPSON.
